UNITED STATES PATENT OFFICE.

OSCAR CALVIN McBRIDE, OF GRANITE, OKLAHOMA, ASSIGNOR TO WILKIE HORATIO HOLTBY, OF MANGUM, OKLAHOMA.

COTTON-GIN.

1,345,206.

Specification of Letters Patent. Patented June 29, 1920.

Application filed June 26, 1919. Serial No. 306,917.

To all whom it may concern:

Be it known that I, OSCAR CALVIN McBRIDE, a citizen of the United States, and a resident of Granite, in the county of Kiowa 5 and State of Oklahoma, have invented certain new and useful Improvements in Cotton-Gins, of which the following is a specification.

My invention relates generally to improvements in cotton gins, and more particularly to improvements in lint flues thereof.

An important object of my invention is to provide a lint flue with means adapted to automatically operate to discharge the cotton 10 from the lint flue when the pressure therein becomes excessive by reason of the cotton clogging in the lint flue due to the improper action of the condenser or to other causes.

Another object is to provide a device of 20 this kind which will not necessitate any special construction of gin or condenser, and which will not in any way interfere with the normal operation of the cotton gin as a whole.

Other objects and advantages reside in certain novel advantages of the construction, arrangement and combination of parts which will become apparent as the description 30 proceeds, reference being had to the accompanying drawings forming a part of this specification, and in which:—

Figure 1 is an elevational view of my invention, parts being broken away for the sake of illustration,

Fig. 2 is a vertical cross section on the line 4—4 of Fig. 1, and

Fig. 3 is a detail sectional view of the spring catch and adjacent structure, the 40 parts being exaggerated and the curvature of the lint flue wall and door being neglected for the sake of illustration.

Referring to the drawing, it will be seen the numeral 5 indicates a lint flue which 45 leads from the cotton gin, (not shown) to the condenser. The condenser may be of any desired type or construction and is shown diagrammatically for the sake of illustration, as including a casing 6 and a 50 screen roller 7. The cotton is fed by means of a forced draft from the gin to the condenser in the usual manner as shown by the arrows in Fig. 1.

The lint flue 5 is usually of circular cross section as shown in Fig. 2, and is provided 55 with an opening 8 in the wall thereof which constitutes the vent. A closure, preferably in the form of a door 9 is provided for the opening and hinged thereto at its lower end as at 9'. Any suitable means which will 60 maintain the door in closed position against normal pressure in the flue, but which will allow the door to open to discharge the cotton from the flue when the pressure becomes 65 excessive, is associated with the door. This 65 means preferably consists of spring catch 10 adapted to coöperate with the door so as to allow the door to swing outwardly under the influence of excessive pressure so as not to 70 impede the discharge of the cotton from the flue but to hold same closed against normal pressure.

The spring catch 10 comprises a bracket portion consisting of a base 11 secured to the wall of the lint flue by means of bolts and 75 nuts 12 or the like. Upstanding ears 13 are formed integral with the base and are provided with aligned apertures to receive the pivot bolt 14 mounted therein. A trip 15 is mounted on the pivot bolt 14 and has its 80 lower end 15' bearing against the upper end of the door 9. This trip has its upper end bent around to form a journal by which the trip is mounted on the pivot bolt and this upper end after completing the journal is 85 then bent back on itself and extends upwardly and then outwardly substantially at right angles, to form a trip arm 16. A blade spring 17 is secured to the upper portion 90 of the bracket 11 preferably by means of the bolts and nuts 12 which also serve to secure the bracket to the lint flue as previously described. The lower portion of the spring 17 bears against the trip arm 16 and tends to maintain the trip in active position 95 resiliently holding the door 9 closed as shown in full lines in Fig. 3, or in inactive position with the trip clear of the door, as shown in dotted lines in Fig. 3. This double action of the spring 9 is due to the position 100 of the pivot bolt 14 with respect to the arrangement of the trip, trip arm and spring itself.

As is well known in the art, the cotton is fed from the gin through the flue under 105 forced draft to the condenser. At times,

however, the condenser does not operate properly and the cotton clogs in the rollers and adjacent structure of the condenser and backs up through the lint flue. If this condition is not promptly discovered the cotton will continue to back up until it enters the gin and in this event, the gin saws or rollers incur serious damage.

In my invention when the condenser 10 clogs and the cotton backs up in the lint flue, the resultant increase of pressure due to the interrupted passage of the forced draft acts upon the door 9 and forces the same outwardly against the action of the 15 trip arm 15 which tends to hold the same closed by virtue of the action of the spring 17. As the door 9 moves outwardly the trip 15 is also moved outwardly and the trip arm 16 moves upwardly. After the trip 20 arm 16 moves upward beyond the horizontal plane of the pivot bolt 14 the effective action of the spring 17 with respect to the trip 15 is reversed and the trip is then thrown upwardly to the position shown in dotted lines in Fig. 3 and is held in this position. The door then falls freely outward and the 25 cotton flows freely out of the opening. In this manner any possibility of the cotton backing up into the gin proper and thereby 30 damaging the same is effectively precluded.

After the clogging has been relieved, the door is closed and the trip reset by seizing the portion 15' and pulling the same down to position near the door. The trip snaps 35 against the door and holds the same closed, though effective to automatically operate to allow the same to open as previously described.

I claim:—

40 1. An improvement in cotton gins comprising, a lint flue, in which the cotton is conveyed from the gin to the condenser under forced draft, provided with an opening, a door for said opening, a bracket arranged 45 adjacent said door, a trip pivotally mounted on said bracket having a trip arm and a spring mounted on said bracket and bearing against said trip arm whereby said trip maintains said door in closed position 50 against normal pressure in said lint flue and allows such door to open outwardly when said pressure becomes excessive and the lint in said flue is in danger of backing up into the gin.

55 2. An improvement in cotton gins comprising a lint flue, in which the cotton is conveyed from the gin to the condenser under forced draft, provided with an opening, a door for said opening, a bracket arranged 60 adjacent said door and having apertured ears, a pivot bolt mounted in said apertured ears, a trip journaled on said pivot bolt having an extension therefrom forming a trip arm and a blade spring secured to said

bracket and bearing against said arm substantially as and for the purpose set forth. 65

3. An improvement in cotton gins comprising, a lint flue, in which the cotton is conveyed from the gin to the condenser under forced draft, provided with an opening, a door for said opening, a bracket arranged adjacent said door, a pivot bolt mounted upon said bracket, a trip journaled on said pivot bolt and engaging the door and having a trip arm adapted in closed position of 70 the door to be disposed below the fulcrum of the trip and a spring mounted upon the trip and bearing against the trip arm whereby the trip arm tends to maintain the door closed when the same is in closed position 75 and is released to allow the door to freely open when the door is moved upwardly a predetermined distance against the action of the spring.

4. An improvement in cotton gins comprising a lint flue, in which the cotton is conveyed from the gin to the condenser under forced draft, provided with an opening, a door for said opening, a bracket arranged adjacent said door, a pivot bolt mounted on 80 said bracket, a trip having its upper end bent around to form a journal by which the trip is mounted on the pivot bolt and bent back on itself and extended upwardly and then outwardly to form a trip arm, and a spring secured on the bracket and bearing against said trip arm substantially as and for the purpose set forth. 85

5. An improvement in cotton gins comprising a lint flue in which the cotton is conveyed from the gin to the condenser under forced draft, provided with an opening, a closure for such opening and a spring actuated trip adapted to hold said closure in shut position against normal flue pressures in 100 said lint flue and permit said closure to open to allow a discharge of lint from said lint flue when the pressure in said lint flue is excessive and the lint is in danger of backing up into the gin. 105

6. An improvement in cotton gins comprising a lint flue in which the cotton is conveyed from the gin to the condenser under forced draft, provided with an opening, a closure for such opening, and a trip adapted to hold 115 said closure in shut position against normal flue pressures in said lint flue and permit said closure to open to allow a discharge of lint from said lint flue when the pressure in said lint flue is excessive and the lint is in 120 danger of backing up into the gin.

7. An improvement in cotton gins comprising a lint flue in which the cotton is conveyed from the gin to the condenser under forced draft, and provided with an opening, 125 a closure for said opening, and means for normally maintaining such closure shut and permitting said closure to open and allow

free discharge of the lint from the flue when the lint is in danger of backing up into the gin.

8. An improvement in cotton gins comprising a lint flue in which the cotton is conveyed from the gin to the condenser under forced draft, and provided with an opening,

a closure for said opening, and spring means for normally maintaining said closure shut and permitting said closure to open and allow free discharge of the lint from the flue when the lint is in danger of backing up into the gin. 10
